CLAIM

The ornamental design for a point-of-sale terminal, as shown and described.

DESCRIPTION

1. Point-of-sale terminal

Fig. 1.1 is a front perspective view of the point of sale terminal;

Fig. 1.2 is a rear perspective view of the point of sale terminal shown in Fig. 1.1;

Fig. 1.3 is a front elevation view of the point of sale terminal shown in Fig. 1.1;

Fig. 1.4 is a rear elevation view of the point of sale terminal shown in Fig. 1.1;

Fig. 1.5 is a right side elevation view of the point of sale terminal shown in Fig. 1.1;

Fig. 1.6 is a left side elevation view of the point of sale terminal shown in Fig. 1.1;

Fig. 1.7 is a top plan elevation view of the point of sale terminal shown in Fig. 1.1; and

(Continued)

Fig. 1.8 is a bottom plan view of the point of sale terminal shown in Fig. 1.1;

1 Claim, 8 Drawing Sheets
